AIR CONDITIONING APPARATUS

Lawrence A. Philipp, Detroit, Mich., assignor to
 Nash-Kelvinator Corporation, Detroit, Mich., a
 corporation of Maryland

Application June 19, 1939, Serial No. 279,807

1 Claim. (Cl. 62—139)

This invention relates to air conditioning apparatus.

This application is a continuation in part of my application Serial No. 43,076, filed October 1, 1935 for Air conditioning apparatus.

One of the objects of my invention is to provide an improved method of maintaining a proper temperature within an enclosure and of controlling the relative humidity within said enclosure.

Another object of this invention is to provide an improved forced air conditioning unit which maintains a proper temperature within an enclosure, circulates effectively the air therein and also maintains control of the relative humidity of the enclosure.

Another object of my invention is to provide an improved method of reducing the temperature of the air within an enclosure to be conditioned while at the same time maintaining a high relative humidity within said enclosure.

Another object of this invention is to provide an improved forced air cooling unit in which one or more perforate heat absorbers preferably of large face or frontal area and of extremely shallow depth, are arranged in a novel manner to lower the temperature of air and to maintain control over the relative humidity of the air to be conditioned.

Another object of my invention is to provide an improved forced air cooling unit in which the air to be conditioned is circulated at a relatively high velocity through a finned heat absorber of large frontal area and of extremely shallow depth to effect a lowering of the temperature of the air but a few degrees with a consequent minimum reduction of the relative humidity of the air to be conditioned.

Another object of this invention is to provide improved devices for adding moisture to air which is to be maintained at a proper temperature and a high relative humidity.

It is also an object of my invention to provide a forced air conditioning unit comprising a vertically disposed casing for enclosing an air passage with a centrifugal fan for drawing air upwardly therethrough and throwing it transversely from the upper ends, and having heat and moisture absorbing means disposed at a lower level in the passage for successive association with the stream of air circulating upwardly therethrough.

Still another object of my invention is to provide such a unit comprising an elongated air convection casing enclosing convection forcing means with successive air conditioning elements

and having its opposite ends partially obstructed whereby air is drawn into and discharged from the passage transversely.

Further objects and advantages of the present invention will be apparent from the following description, reference being had to the accompanying drawings, wherein a preferred form of the present invention is clearly shown.

In the drawings:

10 Fig. 1 is a vertical sectional view showing an air conditioning unit constructed in accordance with my invention;

Fig. 2 is a cross sectional view on lines 2—2 thereof;

15 Fig. 3 is a vertical sectional view showing a modification of my improved air conditioning unit;

Fig. 4 is a top plan view of the modification shown in Fig. 3;

20 Fig. 5 is a top plan view of a modification of the air conditioning unit shown in Figs. 3 and 4;

Fig. 6 is a side view of another modification of my improved air conditioning system;

Fig. 7 is an end view of the modification shown in Fig. 6;

Fig. 8 is a vertical sectional view (partly broken away) of another modification of my improved air conditioning unit;

25 Fig. 9 is a vertical sectional view of a modification (showing controls) of my improved air conditioning unit shown in Fig. 8;

Fig. 10 is a top plan view of the air conditioning unit shown in Fig. 9;

Fig. 11 is a vertical sectional view showing another modification of my improved air conditioning unit;

Fig. 12 is a top plan view of the unit shown in Fig. 11.

In the conditioning of enclosures, it frequently is desirable to maintain a low temperature and a high relative humidity. This is particularly true in the case of preservation of certain types of food and in certain industrial processes. It is with this problem that we are primarily concerned.

30 In forced air circulation cooling, the air to be conditioned is generally circulated over a finned or extended coil or cooling unit. Where mechanical refrigerating systems are used, volatile refrigerant is evaporated within the extended surface coil whereby the temperature of the air flowing over the surface of the coil is lowered and some of the moisture in the air is removed. The extent of temperature reduction and the 35 quantity of moisture removed are determined by

certain factors which are herein briefly considered.

When air is forced over a cooling surface some of the air and water molecules strike the surface of the coil and thereby assume the temperature of the coil. Other molecules flow through the coil and do not come into contact with the cooling surface. The temperature of the air and water vapor mixture which leaves the coil or cooling surface is determined by the number of molecules which are brought into contact with the cooling surface and the temperature of the cooling surface. The number of molecules brought into contact with the cooling surface is determined largely by the length of the path of possible contact of the molecules with the cooling surface in the depth of the coil, the velocity of the air over the coil and the degree of turbulence of the air through the coil.

The temperature of the air which contacts the coil and the moisture content of the air which contacts the coil is therefore determined by the temperature of this air and the temperature of the coil. Moisture in the air which contacts the coil mixes with the moisture which has not contacted the coil so that the final moisture content of the air leaving the cooling unit is determined by the initial moisture content of the entering air, the temperature of the coil and the ratio of the air which has contacted the coil to the total quantity of air which has been forced over the coil.

I have found that the magnitude of the lowering of the temperature of the air across the coil has a very large effect upon the relative humidity of the air while the temperature of the coil has only a small effect. That is, more specifically, the greater the lowering of the temperature of the air circulating through the coil the greater the dehumidification; the smaller the lowering of the temperature, the less the dehumidification. Moreover, I have found a coil of extremely large frontal area and of very shallow depth to be one which best accomplishes only a small lowering of temperature of the air circulating thereover although the temperature of the refrigerant may be extremely low. Circulating air at a relatively high velocity over such a coil insures a very small lowering of temperature with little, if any, dehumidification.

In accordance with my invention I have provided an improved forced air circulation conditioning unit which includes a perforate heat absorber having a large frontal cooling area and an extremely shallow depth over which air is circulated at a relatively high velocity. This heat absorber either alone or in conjunction with others of the same design, I have arranged in various novel positions with other conditioning elements to obtain a reduction of temperature of, preferably, not more than five degrees with a consequent minimum reduction of relative humidity of the air circulating thereover. Furthermore, since the lowering in the air temperature across the coil is so small, a maximum average temperature difference between air and refrigerant may be maintained resulting in maximum cooling capacity for the cooling unit. A lower refrigerant temperature can, if desired, be maintained resulting in large coil capacity without materially affecting the capacity of the condensing unit.

I have also provided in my improved air conditioning system various means for adding moisture to the air to be conditioned, in order to in-

sure the maintenance of a high relative humidity as will be shown below.

Referring more specifically to the drawings, my air conditioning unit comprises a casing or air tunnel 3 which is mounted in a vertically disposed position upon pedestal brackets 5 depending from the lower edge thereof and resting on the bottom of a flat pan shaped receptacle 7. The pedestal brackets 5 may be secured to the air tunnel 3 in any suitable manner, as by welding for example, and they are sufficiently elongated to support it in spaced relation above the drip pan 7 to define a vent aperture 9 extending peripherally around the lowermost edge of the tunnel. The air tunnel casing 3 and the drip pan 7 are preferably of sheet metal of square or rectangular cross section.

For drawing air upwardly through the air convection passage 10 enclosed by the vertical casing 3, I provide a centrifugal fan 11 mounted on the upper end of a shaft 13 extending vertically from a suitable electric motor 15 which is mounted at an intermediate position within the casing on transversely extending brackets 17. The motor supporting brackets 17 may be provided with abutting end portions 19 to the side walls for attachment to the casing in any suitable manner, as by welding, for mounting the motor at a suitable position such that the centrifugal fan 11 on the upper end of its shaft 13 is disposed above the upper edge of the air tunnel casing.

At a position below the electric motor a perforated air cooling structure 21 is mounted in transversely disposed position in the air convection passage 10. Such a cooling member 21 may comprise reversely bent coils of a refrigerant receiving conduit 23 having heat conductive fins 25 secured thereto for increasing the thermal coupling with the air in a well known manner. The air cooling member 21 is designed in accordance with my invention to provide only a small lowering of temperature with a minimum of dehumidification of air circulating at a very high velocity, as is hereinafter set forth. It composes a sectional structure conveniently mounted in the square or rectangular air tunnel casing.

Under unusual atmospheric conditions as in very humid summer weather the air to be cooled may have approximately one hundred percent humidity and at such times a small amount of moisture may be condensed upon the surfaces of the cooling member. In order to catch and hold such condensed moisture in the air stream I provide a foraminouslike member or screen 26 extending transversely across the air convection passage 10 under the air cooling member 21. For this purpose a very fine woven wire screen may be utilized which is secured around its edges to the side-walls of the air tunnel casing 3 in any suitable manner. By this arrangement any air carried moisture which is condensed upon the cooling member 21 drops down upon the screen 26 where it is supported as very fine globules in the air stream, where it is substantially revaporized and maintains the humidity.

The open upper end of the air convection tunnel 3 is covered by a sheet metal cap 27 which is supported in spaced relation above the upper edge of the casing by brackets 29 which may be secured to both in any suitable manner. The cap is spaced above the upper edge of the tunnel casing to provide a suitable air vent aperture 31 extending peripherally around the edge thereof.

In operation the electric motor 5 is energized from the service mains through any suitable energizing circuit which may be controlled man-

ually or automatically by humidity or temperature responsive devices in any manner well known to those skilled in the art. The electric motor is adapted to drive the centrifugal fan 11 at a high rate of speed. The latter throws the air transversely from the casing 3 through the upper vent, as indicated by the arrows. As the air is thus discharged from the upper end of the air convection passage 10, it is replaced by air which enters the lower end of the convection passage through the lower peripheral vent aperture as indicated by the arrows. After the air enters through the lower vent it passes upwardly through the air convection passage passing successively through the fine air screen and the perforated air cooling member 21.

A uniform flow of high velocity air up through the finned coil is thus produced and the slightly cooled air is blown out of the top of the unit in a horizontal plane thus distributing the air uniformly in all directions.

In Figs. 3 and 4, there is shown a modification of my improved forced air conditioning unit which like that shown in Figs. 1 and 2 is designed to be used in cooling enclosures, particularly meat keepers, food storage rooms, refrigerators, industrial rooms and the like. Numeral 40 designates a vertical passageway whose four walls consist of finned heat absorbers or refrigerant evaporators adapted to cool the air circulating therethrough. These heat absorbers are preferably extended surface coils of shallow depth single rows designated by the numbers 42, 43, 44 and 45 and are so designed that air circulating through them at a relatively high velocity will suffer a lowering of less than five degrees in temperature, preferably in the neighborhood of two or three degrees, particularly where it is desired to cool enclosures wherein meat is kept. The magnitude of the frontal area of the coil is adjusted in accordance with the quantity of air being circulated thereover to obtain the optimum result as will be readily understood. They are supported in their rectangular position by means of angle irons 46 and 47 placed at each corner of the rectangle. A drain pan 50 is attached to the lower ends of the angle irons 46 for collecting moisture condensed from the cooling coils. A fan 52 operably connected to a motor 53 by a shaft 54 serves to draw in air through the cooling coils at a relatively high velocity. The motor 53 is supported from the sides of the passageway near the top of the passageway 40 by cross-pieces 56. Current is supplied to this motor by service mains (not shown) which may, if desired, be under the control of either a thermostat or humidostat. The heat dissipating unit, preferably a condensing unit of a mechanical refrigerating system, associated with the cooling coils is not shown but may be of any conventional type.

In operation, my improved unit is placed in an enclosure wherein a temperature of, for example, 40° is to be maintained and a high relative humidity is desired. It is preferably suspended from the ceiling of said enclosure. Air is drawn in through all four heat absorbers at a rapid rate by the fan 52. Its temperature is reduced about two or three degrees with little, for example, 4% reduction in relative humidity under certain high humidity conditions, or no reduction in relative humidity under other conditions. This treated air is then expelled through the top of the passageway; strikes the ceiling and mushrooms out into the enclosure where it

mixes with the air therein to maintain the temperature at 40°. The small lowering of temperature is adequate to take care of the heat leakage into such enclosures and yet the relative humidity of the enclosure is not appreciably affected, thereby avoiding objectionable dehydration of meats and foods contained therein. Thus it will be seen that a unit of this kind will cool a large quantity of air and diffuse it quickly and completely into the untreated portions of an enclosure to be conditioned. It is readily adaptable by varying the design of the coils in accordance with the quantity of air to be treated to condition the air within small or large enclosures. And by selecting coils of a design in accordance with that hitherto described effective cooling may be accomplished with very little reduction in relative humidity.

In Fig. 5 there is shown a forced connection unit which differs slightly from that shown in Figs. 3 and 4. A rectangular vertical passageway 58 is provided which two finned refrigerant evaporators or heat absorbers 60 and 61, preferably of the extended surface and shallow depth type, forming two opposite walls of the passageway. These heat absorbers are designed to effect only a small lowering of temperature, preferably not more than five degrees. This is accomplished, as pointed out above, by adjusting the ratio of frontal area to depth of the heat absorber and the speed of the air flowing through the heat absorber. That is, a high ratio of frontal area to depth and a high velocity of circulating air results in small lowering of temperature with practically no dehumidification. These coils are associated with suitable heat dissipating or condensing means of conventional type. The other two walls consist of filters 62 and 63 which are primarily adapted to remove odors from the air and any fine particles of material in the air. A drain pan 64 supported from the walls of the passageway serves to collect moisture condensed from the air by the heat absorbers 60 and 62. A fan 66 driven by a motor 67 by means of a shaft 68 serves to draw air through the perforate heat absorbers 60 and 61 at a high velocity and through the filters 62 and 63. An opening in top of the passageway 58 allows the treated air to escape into the enclosure to be conditioned.

In operation, air is drawn rapidly through the perforate heat absorbers 60 and 61 and through the filters 62 and 63 by the fan 66 whereby it is purified and cooled. Any moisture condensing out collects in the drain pan 64. The treated air is expelled out the top of the unit where it intermingles with the untreated air of the enclosure to be conditioned.

In Figs. 6 and 7, another modified form of my improved forced convection unit is shown. A horizontal passageway 78 is provided having two sides and the bottom formed of perforate heat absorbers or refrigerant evaporators 71, which are preferably extended surface and shallow depth cooling coils designed to effect a lowering of not more than five degrees in temperature of a rapidly flowing stream of air. Any suitable heat dissipating or condensing unit (not shown) is provided for supplying heat absorbing means to the coils. The top of the passageway has a cover 72 which may be of finished sheet metal if desired. A motor 74 is supported in the middle of the passageway by any suitable means (not shown). Shaft 75 of motor 74 operates fans 77 which serve to draw air rapidly through the heat absorbers

and expel it through the ends of the passageway. A drain pan 78 is supported from the walls of the passageway for collecting any moisture condensed by the cooling coils.

In operation, untreated air is drawn in laterally through the sides of the passageway and vertically through the bottom of the passageway at a high velocity. It is cooled not more than five degrees by the heat absorbers and some moisture may be condensed out. This treated air is then expelled out both ends of the horizontal passageway 70 to mix with the untreated air of the enclosure.

In Fig. 8 there is shown another modification of my improved forced convection unit in which a device for adding moisture to the circulating air is provided. The unit comprises a vertical passageway 80 having walls consisting of finned heat absorbers or refrigerant evaporators 82 for cooling the air to be treated. These heat absorbers are preferably cooling coils having extended surface and a short path of contact of air with cooling surface so as to reduce the temperature of a rapidly moving stream of air not more than five degrees. A fan 84 is operatively connected to a motor 85 by means of a shaft 86 for drawing in air through the heat absorbers 82 at a relatively high velocity. The motor 85 is supported near the top of the passageway from the sides thereof by means of cross pieces 88. A pan 90 is attached to the walls of the passageway and below the heat absorbers for holding a supply of water for humidifying purposes and for collecting any moisture that may be condensed by the heat absorbers. Water is supplied to the pan from any suitable source by a conduit 92 having a valve 93 therein for regulating the flow therethrough. An overflow conduit 94 is provided for drawing off excess water. In order to lift the water in pan 90 to a point where it may humidify the air circulating through passageway 80, a funnel-shaped centrifugal lift 96 is provided. This centrifugal lift is operatively connected to the motor 85 by a shaft 97 whereby it is rotated at such speed that water is picked up by it at its lower end and carried upwardly and outwardly until it strikes a narrow cylindrical shield 98. The latter deflects the water downwardly in a sheet of water. The shield 98 is supported from the sides of the passageway by a plurality of short arms 99. If desired, the entire unit may be raised upon legs 100 to form a floor model conditioner.

In operation, untreated air is drawn in through the heat absorbers 82 at a high rate of speed and is thereby cooled a few degrees. It then circulates through the sheets of water falling from the deflector shield 98 picking up water to increase its relative humidity. This cooled air of high relative humidity is expelled out the top of the unit by the fan 84 into the enclosure to be conditioned.

In Figs. 9 and 10, there is shown a forced air conditioning unit like that shown in Fig. 8 with the added feature of a humidity control. Numeral 102 designates a vertical passageway having perforate heat absorbers 104, preferably of the aforementioned type, disposed in the walls thereof. A fan 106 connected to a motor 107 by a shaft 108 serves to circulate air through the unit. The motor is supported at the top of the passageway by crosspieces 110. Disposed at the bottom of the unit beneath the heat absorbers is a pan 112 which is adapted to hold water for humidifying purposes. A conduit 114 under control of a valve 116 supplies water to the pan and a conduit

118 carries away any overflow. Water is lifted from the pan by means of a centrifugal lift device 118 which is rotated by means of the motor 107 through the medium of a shaft 119. The water so lifted impinges upon a deflecting shield 120 and is returned to the pan as a cylindrical sheet of water. A cup-shaped container 122 having an opening 123 in the bottom for admitting water is provided on the floor of pan 112 being however somewhat raised therefrom. The lower end of the centrifugal lift dips into this container. A closure member or stopper 124 is adapted to sit on the opening 123 for controlling the flow of water into the container 122. The stopper is moved up or down by means of a small metal cylinder 126 that slides in a cylindrical chamber 127 under the influence of a solenoid coil 128. The stopper 124 is connected to the metal core 126 by means of a rod 130 which extends through a small opening in the bottom of the pan 112. This opening is adapted to be closed when the coil 128 is energized by means of a closure member 131. Current is supplied to the solenoid coil through wires 133, 134 and 135 and through a humidostat 136.

In operation, when there is no demand for humidification, no current flows to the solenoid. The latter not being energized can not raise the core 126 and the closure member 124 seals the opening 123 thereby allowing no water to enter the container 122. The rotation of the centrifugal lift 118 accomplishes nothing. When there is a demand for humidification as will be indicated by the humidostat 136 closing the circuit to the solenoid, the solenoid is energized, raising the closure member 124 from its seat allowing water to enter the container 122. The centrifugal lift 118 then lifts water into the path of the circulating air. The operation of the unit is otherwise the same as that of the unit shown in Fig. 8.

In Figs. 11 and 12, another modification of my improved forced air convection unit is shown. In this unit another system of adding moisture to the air is shown. A vertical passageway 148 is formed by four finned heat exchangers or refrigerant evaporators 142 which are preferably adapted to be supplied with a volatile refrigerant. These heat exchangers are similar in design to those already mentioned. They preferably have large frontal area and shallow depth. The ratio of frontal area to depth is large in any case but the actual ratio is determined by the quantity of the air being circulated thereover as pointed out above. To effect only a small lowering of temperature with a minimum of dehumidification both the ratio of frontal area to depth and the velocity of the air circulating over the coil should be kept as large as conveniently possible. A fan 144 operatively connected to a motor 145 by a shaft 146 serves to circulate air through the unit. The motor 145 is supported from the sides of the passageway by cross-pieces 148. A drain pan 150 is attached to the bottom of the passageway. The entire unit may be supported on legs 152 if desired. In order to add moisture to the air circulating through the unit a rectangularly shaped trough 154 is provided into which water is run from a water supply conduit 156. The trough is supported on the cross-pieces 148. The conduit 156 may be controlled by a manually operated valve 158 or by a humidostatically operated solenoid valve 160 as desired. Water running into the trough 154 flows over and falls in sheets to the drain pan 150 from which it flows through a

conduit 162. Air drawn in through the heat absorbers 142 circulates through the sheets of water and picks up moisture thereby increasing their relative humidity. The operation of the unit is otherwise the same as that of the unit shown in Fig. 8.

Although only a preferred form of the invention has been illustrated, and that form described in detail, it will be apparent to those skilled in the art that various modifications may be made therein without departing from the spirit of the invention or from the scope of the appended claim.

I claim:

An air conditioning system comprising, in combination, perforate heat absorbers consisting of a plurality of single rows of extended surface finned coils of shallow depth, arranged to produce a vertical passageway, supporting means disposed at the ends of each row of coils and to which said coils are connected to produce said vertical passageway, a drain pan attached to said supporting means and constructed for substantially obstructing one end of said passageway, and circulating means supported by said coil supporting means and positioned within said passageway opposite to said drain pan.

LAWRENCE A. PHILIPP.
